UNITED STATES PATENT OFFICE.

MAJOR ROMEYN JEWELL, OF ROCHESTER, NEW YORK, ASSIGNOR TO THE SCHLICHT & FIELD COMPANY, OF SAME PLACE.

SHELF-BRACKET.

SPECIFICATION forming part of Letters Patent No. 425,326, dated April 8, 1890.

Application filed October 14, 1887. Renewed November 11, 1889. Serial No. 329,850. (No model.)

To all whom it may concern:

Be it known that I, MAJOR ROMEYN JEWELL, of Rochester, in the county of Monroe and State of New York, have invented certain improvements in Shelf-Brackets, of which the following is a specification.

Various plans have hitherto been devised for supporting shelving by means of vertically-adjustable brackets. These brackets were commonly attached to a wall or a standard adjacent to a wall, from which they extended outward, being supported wholly at their inner or rear ends. When thus arranged the weight of the load upon the shelves tended to tip the brackets and their supports forward, so that it was necessary in the case of shelving intended for books and for other heavy bodies to construct the brackets and their supports of great strength and to screw the supports very firmly in position.

The aim of my invention is to avoid certain of the objections incident to the ordinary construction, to admit of the parts being made lighter and cheaper, and to prevent the possibility of the shelving tipping forward.

In carrying my invention into effect I reverse the ordinary arrangement. Instead of supporting the brackets upon or next to the wall I support them on standards arranged at a distance from the wall, so that the overhanging or unsupported end of the bracket stands nearest to the wall, in consequence of which the weight carried by the bracket tends to tip the bracket and its standard toward instead of away from the wall.

My invention also consists in various details of construction pertaining to the bracket and its supporting devices.

In the accompanying drawings, Figure 1 represents in side elevation a bracket constructed and supported in accordance with my invention. Fig. 2 is a top plan view of the same. Fig. 3 is a horizontal section on the line 1 1. Fig. 4 is a perspective view of the bracket in modified form.

Referring to the drawings, A represents a floor or base, and B a vertical wall or other rigid vertical support.

C represents a metal post or standard

erected in a vertical position upon the floor and at a distance from the wall greater or less, according to the width of the shelving to be employed. At its lower end this post is seated in a fixed plate D or otherwise secured to the floor, while at its upper end it is connected rigidly by a cross bar or bars E to the wall.

I prefer to employ in connection with each post two bars E, brought together at their outer ends and riveted to the post, but separated horizontally at their inner ends and secured to the wall at different points by screws b or equivalent fastening devices. The diverging arms thus applied maintain the upper end of the standard rigidly in position, preventing it from approaching the wall or moving laterally.

The post is preferably made, as shown, of T form in cross-section and provided on its inner edge with a series of notches or teeth c.

F represents a bracket, which may be of any suitable design or configuration, with its broader end connected to and arranged to slide vertically upon the post C. This sliding connection may be of any suitable form, but I commonly construct the bracket of cast metal and unite it to the post by means of wrought-metal straps G G, which are passed around the post and riveted at their ends to opposite sides of the bracket, thus forming a strong and simple connection.

H represents a locking dog or lever, pivoted at e to the bracket and provided at its forward end with a cross pin or roller f, to engage the teeth of the post, and thus support the bracket at the required height thereon. The lever is extended inward, so that the weight of its inner end preponderates and causes it to engage automatically in the teeth. When the bracket is to be raised, it is only necessary to push it upward, as the dog will automatically ride over the teeth and engage therein when the upward pressure ceases. To lower the bracket, it is only necessary to lift the end of the lever, as indicated by dotted lines, whereby it is disengaged from the post to lodge in the recessed inner face of the bracket, which is thus permitted to descend.

The lever may be constructed in any suitable

ble form; but it is preferably made, as shown in the drawings, of a thin metal sheet or strap doubled or bent to a **U** form and passed through a slot *g* in the bracket, the slot serving as a stop to limit its movement.

It will be observed that the post or standard *C* stands at a distance from the wall; that the bracket is supported wholly by this post and extends inward toward the wall, so that any weight applied to the bracket tends to throw the post toward the wall. As a result of this arrangement, it follows that the brackets may be loaded to their full capacity without danger of the structure tipping forward, and that proper connections to the wall may be more easily and cheaply made than under the ordinary construction, in which the entire weight tends to throw the structure forward.

Instead of arranging the post with its toothed edge next to the bracket, as in Fig. 1, the post may be reversed and the bracket arranged to slide against its smooth face, as shown in Fig. 4. In this case a bracket may be cast with ears *h* to engage and slide upon the post. The lever *H* will in this case be extended past the edges of the bar, so that its pin or roller *f* may engage with the teeth on its outer edge, as shown.

While I prefer to connect the bracket with the standard in the manner shown, it is to be understood that my invention includes brackets otherwise formed and connected to the standard, provided they extend from the standard toward the wall, as herein explained.

The connection of the brackets to a support at their forward ends is advantageous not only in the particulars before described, but also in that the adjusting devices are brought to the front, where they may be readily manipulated, and also in that the standards or posts are brought in such position that they may be utilized as a means of supporting the doors, sash, or other front of a case or cabinet, so that the use of a special set of standards as usual for this purpose is avoided.

It will be understood that I propose to erect

a series of posts at suitable distances apart, to mount any desired number of brackets on each post, and to extend the shelving of wood or metal from the bracket of one post to those of the next.

Having thus described my invention, what I claim is—

1. In combination with a wall or equivalent support, a standard fixed at a distance therefrom, a bar or brace to hold the standard away from said support, and a shelf-sustaining bracket mounted on the standard and sustained wholly thereby and projecting toward the wall, whereby the weight applied to the bracket is caused to urge the standard toward the wall.

2. In combination with the base *A* and the vertical wall or support *B*, the vertical toothed post *C*, the brace connecting said post with *D* and holding the top of the post at a suitable distance from the wall, and the vertically-adjustable bracket mounted upon and sustained wholly by the post and extending therefrom toward the wall, as described.

3. In a system of shelving, the toothed post *C* and the sliding bracket *F*, having the straps *G*, and recessed on its inner face, in combination with a locking-dog pivoted in the bracket and provided with a roller on its engaging end, substantially as described.

4. In combination with the toothed standard of **T** form in cross-section, the bracket arranged to slide on the toothless side of the standard and adapted to engage its edges, and the **U**-shaped dog pivoted to the bracket and arranged to straddle both the bracket and the standard and to engage the teeth on the outer side of the latter.

In testimony whereof I hereunto set my hand, this 31st day of May, 1887, in the presence of two attesting witnesses.

M. ROMEYN JEWELL.
